DESIGN FOR A SHOE

Claude H. Daniels, Greenwich, Conn.

Application July 18, 1941, Serial No. 102,212

Term of patent 14 years

To all whom it may concern:

Be it known that I, Claude H. Daniels, a citizen of the United States, residing at Greenwich, in the county of Fairfield and State of Connecticut, have invented a new, original, and ornamental Design for a Shoe, of which the following is a specification, reference being had to the accompanying drawing, forming part thereof.

In the drawing:

Fig. 1 is a perspective view of a shoe showing my new design;

Fig. 2 is a side elevational view of the opposite side of the shoe shown in Fig. 1.

Fig. 3 is a fragmentary plan view of the forepart of the shoe.

I claim:

The ornamental design for a shoe, substantially as shown.

CLAUDE H. DANIELS.
